UNITED STATES PATENT OFFICE.

FRANK J. DELL, OF CINCINNATI, OHIO.

DESIGN FOR A KITCHEN-CABINET.

SPECIFICATION forming part of Design No. 32,238, dated February 13, 1900.

Application filed January 5, 1900. Serial No. 516. Term of patent 7 years.

To all whom it may concern:

Be it known that I, FRANK J. DELL, a citizen of the United States, and a resident of Cincinnati, Hamilton county, State of Ohio, have 5 invented and produced a certain new and original Design for a Kitchen-Cabinet; and I do declare that the following is a description of the invention sufficiently clear, full, and exact to enable others skilled in the art 10 to which it appertains to make and use the same, attention being called to the accompanying drawing, with the reference-numerals marked thereon, which forms also a part of this specification and which shows in a perspective view a kitchen-cabinet embodying 15 my design.

The subject of this invention relates to kitchen-cabinets; and the object is to increase and improve the usefulness as well as appearance 20 thereof by certain shapes, proportions of sizes, arrangement of parts, and configuration, all as described hereinafter and illustrated in the accompanying drawing.

In carrying out this design my kitchen-cabinet is formed to have a box-shaped base 25 part 2, the upper front corner of which is removed throughout its entire length on a curved line, producing a concaved surface 3. The remaining upright part of the front of the 30 base contains two door-panels 4, surrounded by a raised molding 5. The upper part of this concaved surface 3 is filled out with two long and narrow flap-panels 6, occupying together the entire length of this part of surface 3. The outlines of these panels are 35 marked by certain marginal distinctions 7. Above this base part the main body of the case rises up vertically, terminating in a roof-shaped top consisting of four sides 8, sloping

from the central flat apex 9 toward the four 40 sides of the case. The whole is topped off by a top ornament 10, rising from apex 9.

The front of the case between top and base is vertically subdivided by four columns 11, spaced to form three panels. Of these the 45 center one 12 presents a convex surface extending throughout the entire height of the panel and is provided near its lower end with a horizontally-disposed opening 13. The lateral or end panels are alike and consist each 50 of a flat surface 15, occupying the larger part of each from the upper end on down. Below these flat surfaces there are concave flap-panels 16, extending across the space between the two columns, and again below these there 55 are upright fields 17, provided each with three circular projections 18, arranged in a row.

The space in the corner across the top of panels 15 and part way down between them 60 and the adjacent columns is filled in, as shown at 19.

The opposite ends of the base have circular perforations, as shown at 20, and one of the sides of the case is provided in its upper part 65 with a narrow upright opening 21.

Having described my invention, I claim the same as follows:

The design for a kitchen-cabinet, substantially as shown and herein described.

In testimony whereof I have hereunto set my hand, this 2d day of January, 1900, in the presence of two witnesses.

FRANK J. DELL.

Witnesses:

C. SPENGEL,
ALEXIS DARNSMONT.
